UNITED STATES PATENT OFFICE.

HEINRICH ORTGIES, OF ERFURT, GERMANY.

SELF-LOADING PISTOL.

1,386,197.

Specification of Letters Patent. Patented Aug. 2, 1921.

Application filed April 1, 1919. Serial No. 236,814.

To all whom it may concern:

Be it known that I, HEINRICH ORTGIES, citizen of the German Republic, residing at No. 30 Cyriakstrasse, in the city of Erfurt, 5 Germany, have invented certain new and useful Improvements in Self-Loading Pistols, for which I have filed application in Germany February 8, 1918, of which the following is a specification.

10 The present invention relates to self-loading pistols of the kind which are fitted with a removable breech part secured against removal by means of a releasable catch and with a cocking lever which when the butt or 15 handle is gripped is forced inwardly into cocked position and thereby cocks the firing pin. The object of the invention is to provide for such pistols a simple, strong and readily released holding device for the cocking lever, when the latter has been moved 20 into cocked position, which device will automatically snap into the holding position and may be released therefrom by a simple pressure on a push piece, and which, when in 25 holding position, will simultaneously and automatically engage the catch for the breech. According to the invention there is provided in the handle of the pistol a push bolt, which is under action of a spring and 30 axially movable, and which, when the cocking lever is in cocked position engages with a collar in a recess in the latter. This bolt has a nose which, when the bolt is in holding position, *i. e.* when the pistol is ready 35 for shooting, will engage in a groove in the breech part.

The accompanying drawing illustrates an embodiment of the pistol according to the present invention. Figure 1 is a longitudinal section; Fig. 2 is a cross-section along the line 2—2 in Fig. 1, the catch member being released. Fig. 3 is a fragmental sectional view similar to Fig. 1, but showing the catch in locking position; Fig. 4 is a cross-section 45 on line 4—4, Fig. 3; Fig. 5 is a perspective view of the upper portion of the cocking lever, and Fig. 6 is a perspective view of the catch member.

The breech member α of the pistol is held, 50 when the pistol is ready for shooting, by the nose b engaging in a groove in the breech member, said groove permitting a longitudinal movement of the breech member; thereby the breech member is prevented 55 from moving in an upward direction. This nose b , which heretofore was brought into

locking position by the magazine being introduced, is, according to the present invention, fitted to a bolt c , which is guided in the handle m at right angles thereto and is 60 under action of a spring d , which tends to force it outward. In the rear of the handle the cocking lever e is pivoted in known manner, the arm f of which forms likewise in known manner the abutment for the percussive pin spring. According to the present invention the cocking lever is provided with a recess h which encircles the bolt c between the head i and the collar j from right to left. The collar j may engage with a recess k in 70 the cocking lever, corresponding to its form. This will be the case when the lever e is forced inward on the handle being gripped. The spring d will then force the collar j into the recess k , so that the latter encircles the 75 same and it is impossible for the cocking lever to go back. In this position the pistol is ready for shooting, and a continuous firing is possible without any strain on the hand by the cocking lever. When the collar j thus 80 engages in the recess k the nose b will at the same time engage the breech part α , so that it is impossible for the latter to move upward, whether purposely or accidentally. By exerting pressure on the head i of the 85 bolt c the collar is disengaged from the recess k , whereupon the cocking lever is forced back by the action of the firing pin spring and the pistol is safe, as the firing pin spring is relieved. At the same time the 90 nose b is disengaged from the breech member, so that the latter may, when desirable, be removed without any difficulty.

What I claim to secure by Letters Patent of the United States is:—

1. In an automatic pistol, the combination, 95 with a cocking lever having a recess therein; of a bolt mounted for axial sliding movement transversely of the handle of the pistol and provided with a collar conforming to 100 the shape of said recess but normally disaligned therefrom; and a controlling spring acting to automatically shift said bolt axially in a direction to engage said collar in said recess when the cocking lever has 105 been forced inward, whereby said lever will be locked against return movement.

2. In an automatic pistol, the combination, 110 with a cocking lever having a recess therein, of a bolt mounted for axial sliding movement transversely of the handle of the pistol and provided with a collar conforming to

the shape of said recess but normally disaligned therefrom; and a controlling spring acting to automatically shift said bolt axially in a direction to engage said collar in said recess when the cocking lever has been forced inward, whereby said lever will be locked against return movement; said bolt having a presser head which projects exteriorly of the handle to permit the bolt to 10 be pushed inwardly against the action of said spring to disengage said collar from said recess.

3. In an automatic pistol, the combination, with the sliding breech member and the cocking lever, said member being provided with a groove and said lever with a recess; of a bolt mounted for axial sliding movement transversely of the handle of the pistol and having a collar conforming to the shape of 15 said recess but normally disaligned therefrom, said bolt also having a nose for engagement in said groove; and a controlling spring act-

ing to automatically shift said bolt axially in a direction to simultaneously engage said collar in said recess and said nose in said groove, when the cocking lever has been forced inward, whereby said lever will be locked against return movement and said breech member against upward movement. 25

4. In an automatic pistol, the combination, with the sliding breech member and the cocking lever, said member being provided with a groove; of a bolt mounted for axial sliding movement transversely of the handle of the pistol and having a nose engageable 30 in said groove to lock the breech member against upward movement; and a controlling spring acting to automatically shift said bolt axially in a direction to effect the engagement of said nose when the cocking lever has 35 been forced inward.

In testimony whereof I have affixed my signature.

HEINRICH ORTGIES.
